UNITED STATES PATENT OFFICE.

BERNARD M. KRELL AND MICHAEL ZUCKERMAN, OF NEW YORK, N. Y.

FELLING DEVICE FOR SEWING-MACHINES.

1,241,739.

Specification of Letters Patent.

Patented Oct. 2, 1917.

Application filed April 10, 1917. Serial No. 160,940.

To all whom it may concern:

Be it known that we, BERNARD M. KRELL, a citizen of the United States, residing at New York city, in the county of Bronx and State of New York, and MICHAEL ZUCKERMAN, a citizen of the United States, residing at New York city, in the county of Bronx and State of New York, have invented certain new and useful Improvements in Fell-
10 ing Devices for Sewing-Machines, of which the following is a specification.

This invention relates to a feller for sewing machines and has for its principal object to provide a feller for making curved lap seams which curve either to the right or to the left as the seam passes through the machine.

Another object is to provide an easily adjustable feller for sewing on different kinds 20 and thicknesses of material.

These and other objects will appear as the description proceeds.

In order to accomplish these objects we have provided a feller comprising a base 25 piece, a scroll plate of novel construction and relation; and while herein we have described minute details of construction, the invention is not limited to these since the details of construction and combination may 30 be varied without departing from the spirit and scope of the invention as claimed.

In the accompanying drawings, showing by way of example one of many possible embodiments of the invention,

- 35 Figure 1 is a plan of the feller;
- Fig. 2 is a front elevation;
- Fig. 3 is a plan of the base piece;
- Fig. 4 is a left-hand end view of the base piece;
- 40 Fig. 5 is a plan of the scroll plate;
- Fig. 6 is a right hand end elevation of the scroll plate;
- Fig. 7 is a front elevation of the scroll plate;
- 45 Fig. 8 is a plan of the feller showing by dotted lines material during the formation of a fell curved to the right;
- Fig. 9 is a similar view showing the fell curved to the left; and
- 50 Fig. 10 is an inverted rear elevation show-

ing the interrelation of the two fell parts and the feller parts.

The feller herein selected to illustrate our invention consists of a base piece 10 and a scroll plate 11.

The base piece 10 is adapted to rest upon and be attached to the bed of the sewing machine and is provided with a pair of screw holes 12 through which the attaching screws pass.

The rear part of the base piece is elevated and formed into a flat bracket face 14, inclined somewhat to the rear and cut away at its intermediate part so as to form a positioning edge 15 against which may be adjusted the positioning lug 16 stamped from the scroll plate 11.

The scroll plate is provided with a pair of elongated slots 17 through which pass screws 18 into the threaded openings 19 of the bracket face 14, whereby the scroll plate may be held in adjusted position, with or without the lug 16 against the positioning edge 15, as desired.

The left hand end portion 20 of the scroll plate is bent downwardly as at 21, inwardly as at 22, again downwardly as at 23, and outwardly as at 24, thus forming an S-shaped scroll, the portion 24 being further continued, upwardly as at 25 and then further to the right as at 26, thus forming a C-shaped scroll extension.

The left hand edge portion of the bracket face 14 is continued in an overhanging lip 27 disposed above an inwardly curved face 28 merging gradually into the base plate 29 of the base piece 10.

The downwardly and inwardly bent portions 21 and 22 of the scroll plate coöperate with the outwardly and upwardly bent portions 24 and 25 and the rightwardly bent portion 26 to form an upper C-shaped folding and guiding slot 30. Similarly the portions 22, 23, and 24 coöperate with the curved face 28 and the adjacent portion of the base plate 29 to form a lower folding and guiding slot 31 similar to the slot 30 but disposed in the reverse direction, a branch of one slot being received between the two branches of the other slot.

100

By reference to Fig. 5 it will be noted that portions 21, 22, and 23 are cut away at the edge 32 and, therefore, extend in the direction of the feed of the cloth, only about half the distance of the portion 25.

The left hand portion 20 of the scroll plate is continued rearwardly into a slightly downwardly inclined tongue 34. The portion 24 is continued rearwardly in finger 35; 10 while the face 28 and the base plate 29 are continued rearwardly in a curved extension 36. The tongue 34, the finger 35 and the extension 36 terminate at about the same distance to the rear of the feller; and the 15 needle or needles of the machine are disposed to the rear thereof.

The operation of the device is as follows:

The lower section or piece 38 of the work is put upon the base plate 29 and the edge 20 portion thereof moved into the curved lower slot 31 until the edge is substantially in contact with the downwardly bent portion 21. The upper work-piece 39 is placed upon the scroll plate and the edge portion thereof 25 posed in the C-shaped slot 30 with the edge substantially in contact with the downwardly bent portion 23. The pieces 38 and 39 are then passed through the machine and stitched.

30 It will be noted that an imaginary *x* line passed through the edge 32 of the downwardly extending portion 23 and the rear edge 40 of the curved face 28 is inclined considerably to the right relative to the normal direction of feed. This permits the edge of the upper work piece 39 to be inclined to the right whereby the work pieces may be moved through the feller in a rightwardly inclined direction and a rightwardly 35 curved fell 42, as in Fig. 8, produced.

In like manner it will be observed that an imaginary line *y* passed through the rear edge 32 of the downwardly bent portion 21 and the rear edge 44 of the upwardly bent 45 portion 25 is inclined to the left, permitting the edge of the lower work piece 38 to be inclined to the left, whereby a leftwardly curved fell 45, as shown in Fig. 9 may be produced.

50 It is noted that the curved falls can be produced only when the edges of the material are curved, and that the cut-away portions permit the curved edges to assume the proper position.

55 The openings 17 are large enough to permit both longitudinal and angular adjustment of the scroll plate. Both the rightwardly and leftwardly curved falls may be made without adjusting the scroll plate, but 60 if it be desired to make the fell more pronouncedly curved in either direction, the scroll plate is adjusted to incline in that direction, the lug 16 preventing inclination to the right sufficient to close the guiding 65 slots 30 and 31. Because of the shape of

the curve of the edge 27, it is impossible to close the guiding slots by inclining the scroll plate to the left.

By adjusting the scroll plate longitudinally, the width of the lower guiding slot 70 31 is varied, whereby different thicknesses of the material of the lower work piece 38 are accommodated. Different thicknesses of the upper work piece 39 may be accommodated without any adjustment of the upper 75 guide slot 30.

We claim as our invention:

1. In a device of the character described, the combination of a part having a curved face; an S-shaped scroll; and an upwardly 80 curved C-shaped extension scroll joining the S-shaped scroll, the S-shaped scroll coöperating with the C-shaped extension scroll and said curved face to form a pair of C-shaped slots, the arm of one slot being received between the arms of the other slot, said S-shaped scroll being cut away at the middle of its rear part whereby it is much shorter than said C-shaped extension scroll.

2. In a device of the character described, 90 the combination of a part having a curved face; an S-shaped scroll; and an upwardly curved C-shaped extension scroll joining the S-shaped scroll, the S-shaped scroll coöperating with the C-shaped extension scroll 95 and said curved face to form a pair of C-shaped slots, the arm of one slot being received between the arms of the other slot, the upper part of said S-shaped scroll being provided with a rearward extension.

3. In a device of the character described, 100 the combination of a part having a curved face; an S-shaped scroll; and an upwardly curved C-shaped extension scroll joining the S-shaped scroll, the S-shaped scroll coöperating with the C-shaped extension scroll 105 and said curved face to form a pair of C-shaped slots, the arm of one slot being received between the arms of the other slot, the upper part and the lower part of said 110 S-shaped scroll being provided with rearward extensions.

4. In a device of the character described, the combination of a part having a curved face; an S-shaped scroll; and an upwardly 115 curved C-shaped extension scroll joining the S-shaped scroll, the S-shaped scroll coöperating with the C-shaped extension scroll and said curved face to form a pair of C-shaped slots, the arm of one slot being received between the arms of the other slot, the upper part and the lower part of said 120 S-shaped scroll being provided with rearward extensions converging toward each other.

5. In a device of the character described, 125 the combination of a part having a curved face; an S-shaped scroll; and an upwardly curved C-shaped extension scroll joining the S-shaped scroll, the S-shaped scroll coöp- 130

- erating with the C-shaped extension scroll and said curved face to form a pair of C-shaped slots, the arm of one slot being received between the arms of the other slot, 5 said curved face and the upper part and the lower part of said S-shaped scroll being provided with rearward extensions converging toward each other.
6. In a device of the character described, 10 the combination of a base piece provided with a curved face; and a scroll plate secured to said piece and formed with an S-shaped scroll and an upwardly curved C-shaped extension scroll joining the S-shaped scroll, the S-shaped scroll coöperating with the C-shaped extension scroll and said curved face to form a pair of C-shaped slots, the arm of one slot being received between the arms of the other slot, said S-shaped scroll being cut away at 15 the middle of its rear part whereby it is much shorter than said C-shaped extension scroll and said curved face, said curved face and the upper part and the lower part of said S-shaped scroll being provided with 20 rearward extensions converging toward each other, said curved face terminating a distance from the middle part of the S-shaped scroll.
7. In a device of the character described, 25 the combination of a part having a curved face; an S-shaped scroll; and an upwardly curved C-shaped extension scroll joining the S-shaped scroll, the S-shaped scroll coöperating with the C-shaped extension scroll and said curved face to form a pair of C-shaped slots, the arm of one slot being received between the arms of the other slot, said S-shaped scroll being cut away at 30 the middle of its rear part whereby it is much shorter than said C-shaped extension scroll, said curved face and the upper part and the lower part of said S-shaped scroll being provided with rearward extensions converging toward each other.
8. In a device of the character described, 35 the combination of a base piece provided with an elevation and a curved face; and a scroll plate secured to said elevation and formed with an S-shaped scroll; and an upwardly curved C-shaped extension scroll joining the S-shaped scroll, the S-shaped scroll coöperating with the C-shaped extension scroll and said curved face to form a pair of C-shaped slots, the arm of one slot being received between the arms of the other slot, said S-shaped scroll being cut away at 40 the middle of its rear part whereby it is much shorter than said C-shaped extension scroll, said curved face and the upper part and the lower part of said S-shaped scroll being provided with rearward extensions converging toward each other.
9. In a device of the character described, 45 the combination of a base piece provided with an elevation and a curved face; and a scroll plate secured to said elevation and formed with an S-shaped scroll; and an upwardly curved C-shaped extension scroll joining the S-shaped scroll, the S-shaped scroll coöperating with the C-shaped extension scroll and said curved face to form a pair of C-shaped slots, the arm of one slot being received between the arms of the other slot, said S-shaped scroll being cut away at 50 the middle of its rear part whereby it is much shorter than said C-shaped extension scroll, said curved face and the upper part and the lower part of said S-shaped scroll being provided with rearward extensions converging toward each other.
10. In a device of the character described, 55 the combination of a base piece provided with an elevation and a curved face; and a scroll plate secured to said elevation and formed with an S-shaped scroll; and an upwardly curved C-shaped extension scroll joining the S-shaped scroll, the S-shaped scroll coöperating with the C-shaped extension scroll and said curved face to form a pair of C-shaped slots, the one slot receiving between its arms an arm of the other slot, the S-shaped scroll being cut away at its rear 60 whereby it is much shorter than said C-shaped extension scroll or curved face, said face and the end parts of the S-shaped scroll being provided with rearward extensions.
11. In a device of the character described, 65 the combination of a base piece comprising a base plate and an elevation thereon having an inwardly and downwardly curved end face merging into the upper face of the base plate, and a scroll plate angularly and longitudinally and adjustably secured on said elevation and formed at one end into downwardly, inwardly, downwardly and outwardly curved portions forming an S-shaped scroll, the outwardly curved portion 70 being upwardly curved and disposed over the S-shaped scroll to form a C-shaped folding slot, the lower part of the scroll forming, with said downwardly curved end face, a reversed C-shaped slot receiving between 75 its arms an arm of the C-shaped slot.
12. In a device of the character described, 80 the combination of a base piece provided with a curved face and a positioning edge, a scroll plate on said base piece and provided with a shoulder engaging said edge and with a scroll coöperating with said face, and means adjustably securing said plate on 85 said base piece.
13. In a device of the character described, 90 the combination of a base piece provided with a curved face and a positioning edge, a scroll plate on said base piece and provided with a pair of slots and with a shoulder engaging said edge and with a scroll coöperating with said face, and screws passing through said slots into said base piece for 95 adjustably securing said plate on said base piece.
14. In a device of the character described, 100 the combination of a base piece provided with a curved face and a positioning edge, a scroll plate on said base piece and provided with a pair of slots and with a shoulder engaging said edge and with a scroll coöperating with said face, and screws passing through said slots into said base piece for 105 adjustably securing said plate on said base piece.

the combination of a base piece provided with an elevation having a curved end and a cut-away intermediate part forming a positioning edge, a scroll plate provided with 5 a scroll coöperating with said curved end to form a guide slot, means for adjustably securing the plate on the elevation, and a

shoulder formed on said plate and engaging said edge.
